WOOD BURNING HEATER

Samuel B. Kemple, Independence, Mo., assignor to
Four Seasons Woodburning Heater Co., Inc.

Filed Mar. 13, 1974, Ser. No. 450,820

Term of patent 14 years

Int. Cl. D23—03

U.S. Cl. D23—93

Fig. 1.

Fig. 2.

Fig. 3.

Fig. 4.

FIG. 1 is a top plan view illustrating a wood burning heater;

FIG. 2 is a front elevational view thereof;

FIG. 3 is a rear elevational view thereof; and

FIG. 4 is an elevational view of one side thereof, the other side being identical thereto.

I claim:

The ornamental design for a wood burning heater, as shown.
